PRESSURE VENTING DEVICE FOR DRY PIPE SPRINKLER SYSTEMS

Filed Nov. 6, 1930

UNITED STATES PATENT OFFICE

EMIL TYDEN, OF HASTINGS, MICHIGAN

PRESSURE VENTING DEVICE FOR DRY PIPE SPRINKLER SYSTEMS

Application filed November 6, 1930. Serial No. 493,709.

The present invention relates to a dry pipe sprinkler system which is equipped in the apartment protected by it with a thermostatically controlled vent means arranged to be operated for venting the air pressure of the system before the normally closed water discharge heads of the system are opened by the heat of fire in the apartment, so that when said heads are thus opened, the discharge 10 of water will be immediate and not preceded by discharge of air fanning the fire before the water arrives; the purpose of the present invention is to provide means for preventing the discharge of water following the vented 15 air pressure, so that when the thermostatic action causing the venting proved to have been due to conditions not in fact making fire in the apartment, or due to defective condition of the thermostatic action, the water 20 damage unnecessary under such circumstances may be avoided. The invention consists in the elements and features of construction shown and described as indicated in the claims.

25 In the drawing:

Figure 1 is a diagrammatic view showing a dry pipe valve and sprinkler system extending in a building to an apartment to be protected and therein equipped with the devices 30 constituting the invention, certain parts of the dry pipe valve and thermostatically controlled vent apparatus being shown in vertical section.

Figure 2 is a longitudinal section of the 35 pressure venting device, the same being shown in association with the thermostatic device by which it is controlled, the latter being indicated only diagrammatically or in general outline.

40 Figure 3 is a detail section at the line 3—3 on Figure 2.

Figure 4 is a section at the line 4—4 on Figure 3.

45 Figure 5 is a detail section at the line 5—5 on Figure 4.

Figure 6 is a detail section at the line 6—6 on Figure 4.

Figure 7 is a detail section at the line 7—7 on Figure 4.

50 Referring to the drawing: The dry pipe

main valve body is indicated at A, having a familiar form of dry pipe valve consisting in the main valve member, 20, seating at inner and outer concentric seats, 21 and 22, the inner seat being the terminal of the main water supply pipe, B, and the outer seat being the upper end of the enclosing wall of the interseat chamber, 25, which is open for drainage and to atmospheric pressure when the main valve, 20, is seated, and held to its seat by the super-atmospheric pressure in the air pressure region of the system, that is, beyond the main valve and extending up to the normally closed water discharge heads, 40, of the pipe system, 41, in the apartment protected. The valve arrangement by which the interseat chamber is rendered open to atmospheric pressure and to drainage when the main valve is seated, is seen at 60^x, requiring no description here for the purpose of this invention, but may be seen fully described in my Patent No. 1,689,980, dated October 30, 1928.

The thermostatically controlled valve for 75 venting the air pressure independently of the opening by fire heat in the apartment of the normally closed water discharge heads, indicated diagrammatically and as to its entirety at C, in Figure 1, is illustrated in detail in Figures 2 and 3, comprising a chamber, 50, connected, as seen at 51, with a vent pipe, 52, leading preferably from the main discharge and air pressure line, 30, which extends between the main valve, A, and the apartment pipe system, 41, and has the discharge heads at a point, 40, as near as possible to the branching off of said apartment pipe system from the main pressure line, 30.

A valve, 53, arranged to seat at the discharge mouth of the pipe, 52, within the chamber, 50, is carried by a lever arm, 54, pivoted on an upstanding bracket, 55, within the chamber, said valve being arranged to be held by a two-membered toggle or knee-form strut device, 56, 57, whose two members are pivoted together at the knee joint, the lower member, 56, being pivotally attached to the valve at the pivot of the lever, 54, thereto, the upper member, 57, being pivoted to the free end of a spring bar, 59, which is

attached at its other end to the upper end of the chamber for normally reacting inwardly at the free end at which the strut member is pivoted as stated. The right hand end of the 5 chamber—referring to Figure 2—is closed by a flexible diaphragm, 60, at the center of which there is secured by clamping nuts, 61 and 62, and interposed clamping washers, 63, 64, a stem, 65, which within the chamber 10 extends and is operatively connected to the pivot, 56^a, which connects the two strut members at their knee joint; and at the end outside the chamber this stem has a head, 65^a, arranged for cooperation of the thermostatic 15 device hereinafter mentioned for thrusting the stem inwardly with respect to the chamber. At the side remote from the diaphragm, 60, the strut members, 56 and 57, have co-operating stop lugs, 68, 69, arranged to be in 20 contact when the strut is flexed at its knee joint, as seen in Figures 2 and 4, so that the knife edge pivot of the two strut members to each other at their inner edge is very slightly out of alignment with the knife edge 25 pivots at the opposite ends of the strut members at the opposite side of alignment position from said cooperating lugs.

Upon considering the construction as thus far described it may be recognized that upon 30 an attendant pulling the stem, 65, outwardly until the lugs, 68, 69, of the strut members collide, the valve, 53, will be seated, and that, due to the action of the spring bar, 59, on the upper end of the upper strut member, 57, and 35 the fact that the pivots of the strut members on each other is past the point of alignment with the extreme pivots of the two strut members, the valve is locked in seated position against the pressure which may be operating 40 in the pipe, 52. This being the normal or set-up position, the thermostatic device referred to is arranged to open the valve, 53, by releasing a weighted lever, 70, from its normal position shown in full line in Figure 45 2, causing it to swing down and inwardly against the head, 65^a, of the diaphragm stem, 65, driving the stem inwardly and snapping the knee joint of the strut members back past the alignment of the three pivots; whereupon 50 the pressure in the pipe, 52, forces the valve, 53, open, buckling the knee joint still further to the left of the position of alignment and tending to hold the valve, 53, open as long as there is pressure enough to overcome the 55 weight of the valve and its connections.

The thermostatic device, X, for tripping the weighted lever, 70, to operate the pressure-venting device described, is included in the subject matter of my copending application 60 Serial No. 464,940, filed November 10, 1920, and will not be here described in detail, but may be sufficiently understood for the purpose of this application upon noting that it consists of two rods, 71 and 72, of the same metal or metal having substantially the same

co-efficient of expansion under temperature change, the rod, 71, being slender relatively to the rod, 72, so that upon rapid rise of temperature in the vicinity of the device the slender rod is quickly heated through and 70 elongated according to its thermal co-efficient, while during the same short time the heavier rod will not be heated to a sufficient portion of its cross section to experience any substantial elongation due to the temperature 75 change. Means is provided to take advantage of the resulting movement of the free end of the slender rod relative to that of the heavier rod, for operating means for tripping the weighted lever, 70, as above described. 80

It will be understood that upon the operation of a thermostatic device such as shown, or of any other construction arranged for setting in operation means for opening the vent valve, the air pressure is first vented from the system and the escaping air will be followed by water at the vent port, as it would be at each of the discharge heads upon their being initially opened by the heat of fire in the apartment; and if the thermostatically caused operation of opening the vent valve is due to actual fire in the apartment or is immediately followed by fire, the discharge of water following the air would be unobjectionable. But if the thermostatic action 90 occurs when there is no fire to be extinguished in the vicinity of the vent and water discharge following, it is quite important that the damage, under such circumstances unnecessary, which would be caused by the water discharge, should be avoided; and in the construction shown this avoidance is accomplished by constructing the venting device with the chamber shown constituting the initial part of the conduit beyond the vent valve through which the pressure is vented upon the opening of the vent valve by the thermostat, this chamber being of sufficient size to contain water in sufficient quantity 100 and to sufficient depth to buoy a float, 80, of size adequate to operate the vent valve for closing it against the pressure of the water following the vented air, the outlet, 50^a, from this chamber being, as shown, at the upper part, so that before any water is delivered from the chamber, the chamber will be filled with water deep enough to operate the float for closing the valve, and the float being operatively connected with the valve, 53, as illustrated. 110

The operating connection consists of a lever, 91, fulcrumed on the bracket, 55, at a point above the fulcrum of the lever, 54, and connected to and carrying the float at the extremity of the arm, 91^a, the other arm, 91^b, being pivotally connected to the valve-carrying lever, 54, intermediate the valve and the fulcrum of said lever, as by the short link, 54^a. 125

Upon discovering that the thermostatic action opening the vent valve was not caused 130

by actual fire in the apartment, it will be desired to shut off the water and drain the system of water and reset the main valve by admitting air pressure from the source of pressure to the air pressure region of the system, and draining the system; and it is desirable to drain the float chamber and reset the vent valve and thermostat in the same process. But the float chamber cannot be drained in the same manner as the remainder of the system, that is, by flow back through the same passage by which the water inflow occurred, because in the case of the float chamber, the inflow passage being controlled by the vent valve is blockaded against back-flow by the valve being held seated by the buoyant action of the water which is to be drained. The valve cannot be opened until the water is drained from the chamber, and the water cannot be drained from the chamber by the passages through which it entered until the valve is opened. Accordingly, other means must be provided for draining the float chamber while the remainder of the system is being drained.

The means shown for thus draining the float chamber consists in the provision of a pipe, 35, leading from the interseat chamber of the main dry pipe valve as seen at 36 and connected to the float chamber at the bottom thereof, as seen at 36^a, Figure 2, the communication of said pipe with the float chamber being controlled by a valve, 37, carried by an arm 54^b, of the lever, 54, for seating upwardly, that is, in the direction of the inflow, and being therefore held seated by the lever, 54, when the valve, 53, is seated downwardly by the other arm of said lever when the float is buoyed by the water following the air into the chamber. The valve, 37, has its stem connected with the lever arm, 54^b, as seen in Figure 2, with freedom for movement relatively to said lever arm when the lever arm is swung down to the position at which the lever holds the valve, 53, off its seat; and a coil spring, 54^c, interposed on the stem between the lever arm and a stop nut, 54^d, at the upper end of said stem permits movement of the valve relatively to the lever arm even when the valve, 53, is held seated by the float; and accordingly when the venting of the system is in progress the valve 37, may be held seated, and will certainly be held seated when in the venting process the water reaches the valve, 37 because the pipe, 35, will be occupied with water back to the interseat chamber, 25, which at that stage has the drain valve, 60^x, closed, and no flow can take place past the valve, 37, which will accordingly be upheld at seated position by the float, 80. But when after the fire, or when it has been discovered that there is no fire, and the water supply is cut off and the system is drained in the usual manner, the pipe, 35, having free discharge through the inter-

seat chamber, 25, of the main valve, of which the drain valve, 60^x, is open at that stage will open the valve, 37, while the float is still at position for holding the valve, 53, closed, the spring, 54^c, yielding to permit such opening, and the float chamber will be drained and the float lowered regardless of the opening of the valve, 53.

It has been found very essential in a system of this character having a vent valve for venting the system pressure to provide against even the slightest air leakage at any such valve when the valve is or should be closed, since such leakage is liable to cause constantly recurring venting and alarm when there is no fire; and reliance cannot be placed on the automatic means of reseating such vent valve after opening it by fire conditions as described, because such valve preferably and almost necessarily having a rubber or like compressible face member to adapt it for sealing the port, is liable to become slightly deformed by remaining compressed to the seat during the long intervals between occasions for venting, and is not certain after being opened to come back to the seat in exactly the same relation thereto as it has occupied while becoming thus deformed by pressure on the seat; and the resulting misfit of the valve to the seat results in leakage. For this reason there is provided means for stressing the valve, 53, on its seat positively and with sufficient force to ensure complete sealing of the port, said means consisting of a screw, 65^x, set through the upper side of the float chamber impinging against the end portion of the spring bar, 59, beyond the point of attachment of the upper toggle member, 57, to said spring bar. And after the operator has reset the valve by means of the diaphragm stem as above described, he may operate the screw, 65^x, to stress the valve firmly to its seat, compensating any permanent compression and deformation which the valve may have experienced while previously seated.

Upon considering the drainage feature it will be recognized that the fact that when the system is set for fire protection with the main valve closed and held closed by the air pressure in the system beyond the main valve, the interseat chamber is open for free drainage and atmospheric pressure, does not render this connection a vent for the air pressure of the system, so long as the vent valve is held closed by the strut, 56, 57; and that when the vent valve is opened by the thermostat buckling the strut, the resulting venting of the air pressure, causing the main valve to be opened, causes, at the same time, the interseat chamber to be closed against drainage and atmospheric pressure, and open to the water supply pressure, so that water will be liable to reach the float chamber through the pipe, 35, about as soon as through the vent pipe, 52, and the now open vent

valve, 53; and therefore the presence of the connection by the pipe, 35, will not prevent nor delay nor hasten the operation for venting and opening the main valve, nor furnish discharge for the water admitted to the system by the opening of the main valve. But when the water is shut off for draining the system, the interseat chamber being again opened for drainage and to atmospheric pressure, the pipe connection, 35, affords path for draining the float chamber, by-passing the closed vent valve, 53, and vent passage, 52, and permitting the float to fall and open the vent valve, 53, permitting the drainage also of the vent passage, 52.

For the drain pipe, 35, the construction shown takes advantage of and utilizes the pipe shown in my Patent No. 1,689,980, as leading to an alarm valve, and the continuation of the pipe indicated at 35^a, beyond the connection with the vent and float chamber, 50, may be understood as leading to said alarm valve, as marked on Figure 1.

A most important purpose of the provision for venting and controlling the delivery of the vented fluid is to make it possible to utilize the pressure thus derived from the system for operating any fire preventive or protective devices in any part of the protected areas, as for example, opening normally closed water discharge heads, closing normally open fire doors to prevent spread of fire to the apartments thus closed, closing windows to prevent air draft which might fan the fire, etc.

Such purposes may be measurably accomplished by extending the pipe, 50^a, to the different devices which may be operated by the fluid pressure passing the vent valve, 53, when opened by the thermostat.

I claim:—

1. In combination with a dry pipe sprinkler system having a vent passage for the air pressure of the system, said passage being extended for discharge separately from the water discharge heads of the system, and a valve controlling said vent passage, and a temperature-responsive device independent of the water discharge heads of the sprinkler system arranged to operate the vent valve for opening upon predetermined temperature conditions in the apartment protected, said temperature-responsive device being arranged for so operating in advance of the operation of the discharge heads, means for preventing discharge of water following the air from the vent passage consisting of a chamber in the vent passage beyond the vent controlling valve, arranged to collect water passing said valve when open for venting the air pressure; a float in said chamber, and connections between the valve and float by which the float operates when buoyed by the water accumulated in the chamber to reseat 65 the valve.

2. The construction defined in claim 1, having the vent passage beyond the water-collecting chamber leading out from the upper part of said chamber, whereby the chamber becomes filled with water for buoying 70 the float and closing the vent valve before any water can pass out of the chamber by way of the vent passage.

3. The construction defined in claim 1, the vent valve being normally held closed, the construction for so holding it including a foldable strut arranged to be flexed at the connection of its folding members for shortening the effective length to release the valve for opening by the pressure to be 80 vented, and means for so flexing the strut comprising a movable wall member of the chamber in which the valve is located, having operating thrust connection with the strut for folding it when the movable wall member is actuated from the exterior for providing such thrust, and said wall member being exposed for actuation by the temperature-responsive device the valve chamber being extended at the opposite side of the strut from the movable wall member for accumulating water; a lever for carrying the vent valve independently of the strut connection therewith, the float being operatively connected with said lever for moving the latter in valve-seating direction by the rise of the float in the chamber due to the accumulation of water therein.

4. The construction defined in claim 1, the dry pipe system comprising a main valve of the type having two seats for the main valve member with an interseat chamber provided with a drainway which is opened for drainage when the main valve is seated, the vent valve float chamber having a free flow connection from its bottom part with said interseat chamber, whereby said float chamber is automatically drained when the main valve is closed in resetting the system for service after its operation in which said float chamber has become occupied with water.

In testimony whereof, I have hereunto set my hand at Hastings, Michigan, this 3rd day of November, 1930.

EMIL TYDEN.
